PAPER-FEED MECHANISM.

Application filed June 5, 1922. Serial No. 566,094.

The invention relates to mechanism for feeding sheets of paper, especially adapted for feeding successive, individual wrapper sheets, which are coated with adhesive and 5 then applied to articles or packages to form completely enclosing, sealed wrappers for the articles or packages; but the sheet feed mechanism is in some or all of its features adaptable for other purposes.

10 In certain classes of paper handling machines it is necessary that individual sheets, such as wrapper sheets, shall be precisely separated from the stack with careful avoidance of the feeding of two or more sheets at 15 the same time, and that the individual sheets shall be accurately advanced in definite or timed relation to other mechanism and without lateral or angular displacement. It is also desirable in many cases that the 20 sheets shall be fed from the top of the stack. A good example of a paper handling machine in which the above and other requirements exist and are met by the present invention, is a wrapping machine of the 25 general class represented by the patent to William A. Weightman and Charles H. Nitsch, No. 1,426,429, August 22, 1922, sometimes known as a sealed-wrapped package machine, and the present invention is, 30 therefore, shown as especially adapted to the requirements of a machine of that class, and it will be so explained, with the understanding that the feed mechanism per se is not limited in its application to that particular type of wrapping or paper handling 35 machine.

In a sealed-wrapped machine of the type above mentioned, articles, such as cartons, containing various commodities, are advanced in regular order, and individual 40 wrapper blanks, which are usually of thin paper, and usually especially shaped for the particular style of wrap, are advanced from a stack successively in spaced relation 45 corresponding generally to the spaced arrangement of the cartons; each wrapper is adhesively coated on one face as it advances and is then brought in contact with a carton, and it is necessary that the wrapper and 50 carton shall be very accurately registered at the point of initial contact so that subse-

quent wrapping operations may be correctly performed. It has been found to be especially difficult to precisely separate the individual thin, especially contoured wrapper blanks from the stack without the inadvertent feeding of two or more blanks at once; to prevent lateral shifting or diagonal displacement of the blanks; and to advance them with perfect regularity and in 55 accurately timed or spaced relation to other mechanisms which transfer them to the initial assembly or registration position, so that the blanks may be applied with perfect registration to the cartons. It is desirable 60 for convenience in handling and replenishing the stacks to feed the sheets from the top of the stack and the present invention is designed to admit of top feeding. With 65 top feed arrangements difficulty has been 70 experienced in properly advancing or elevating the stack to keep the uppermost sheet always in proper position for feeding, and the present invention provides means operating in connection with the individual 75 sheet feeding mechanism for gradually (or intermittently) elevating the stack and accurately controlling the elevating mechanism for the stated purpose.

The advantages and characteristics of the 80 invention are further sufficiently explained in connection with a detail description of the accompanying drawings, which show an exemplifying structure embodying the invention. After considering this, persons skilled 85 in the art will understand that many variations may be made in structure and adaptation, and it is not intended to limit the invention to details, except as it is defined 90 in the appended claims.

In the drawings:—

Fig. 1 is a vertical, longitudinal section of a representative machine, specifically a wrapping machine of the general type above described, with the invention incorporated 95 therein in one form.

Fig. 2 is an enlarged sectional detail, showing mainly the individual sheet feeding mechanism, in a different position from that shown in Fig. 1.

Fig. 3 is a view similar to Fig. 2 showing the mechanism in still another position.

Fig. 4 is a plan view of the sheet-feed mechanism on substantially the same scale as Figs. 2 and 3.

Fig. 5 is a vertical transverse section approximately in the plane 5—5, Fig. 1.

Fig. 6 is an enlarged section in a longitudinal plane illustrating the stops, feed rolls, and adjacent parts in position to receive a sheet from the stack.

10 Fig. 7 is a similar view showing a sheet advanced by the pusher roll and located against the stops and otherwise held in registered position.

15 A wrapping machine of the type chosen for exemplification of the present specific adaptation of the invention, as sufficiently shown in Fig. 1, has side frame members, one of these members 1 being indicated, and these side members are connected by various 20 transverse members including the members 2, 3, of general channel-section. A glue pot 4 is supported on these transverse frame members. Near the top of the frame is a table 5 over which articles, such as cartons 25 C are advanced by conveyor chains, of which one chain 6 is shown, to a point above the rotary blank-cylinder or platen 7, carried by a shaft 8, mounted in bearings in the side frame members. At one point on its periphery the platen is provided with wrapper blank stops 9 and adjacent to these stops 30 clamping fingers 10 are arranged to clamp the forward margin of a wrapper blank B to the platen. Rearward of the platen is a 35 shaft 11 carrying pulleys 12, and assembly supporting and conveying bands 13 pass about the platen and the pulleys and are accommodated by shallow depressions formed in the platen and pulleys. The shaft 11 40 also carries sprockets 14, and assembly conveyor chains 15, of which one is shown, pass about the sprockets.

45 A dipper roll 16 is mounted on the glue pot, and this carries glue to the gluing roll 17, mounted on a shaft 18. The gluing roll is provided with channels 19 in which fit 50 stripper plates 20 to assist in stripping the wrapper blanks from the glue roller.

55 The wrapping machine has a main drive 50 shaft 21 and the package conveyor chains 6 are driven from this shaft by any suitable positive gear train (not shown). The platen 7 is positively driven from the main shaft in definitely timed relation to the carton 60 conveyor by bevel gears 22 and 23, shaft 24, bevel gears 25, gear 26 and a gear 27 on shaft 8. Gear 27 drives an idler gear 28 on a shaft 29 and this idler gear drives a pinion 30 on shaft 11 to impel the conveyor chains 15 at the same speed as the conveyor chain 6, this also being the same as the peripheral speed of the blank platen 7 and the supporting bands 13.

65 The blank clamping fingers 10 of the platen are operated by any suitable mechanism which does not form a part of the present invention and is not particularly described, although sufficiently indicated in the drawing.

70 The glue roll 17 is continuously driven at a suitable peripheral speed by any suitable gearing, such as a shaft 31, bevel gears 32, vertical shaft 33 and bevel gear 34 engaging another bevel gear on the roll shaft 18. The dipper roll may also be positively 75 driven, for instance, by a gear 35 connected to the glue roll, meshing with a gear 36 on the dipper roll shaft.

76 The blank gripping fingers 10 of the platen are open when the blank stops 9 are at a 80 point approximately below the shaft 8. If at this time a cover blank B has been started over the glue roll and its advancing edge is presented in a true line parallel to the axis of shaft 8 against the stops 9, the blank 85 will be properly seized when the clamping fingers 10 close as the platen rotates slightly beyond the position just indicated, and the rotation of the platen will then draw the remaining portion of the blank over the glue 90 roll so that the blank is properly glued, and the further advance of the platen carries a forward part of the glued blank surface 95 into engagement with the advancing carton C, the leading edge of the carton striking the blank a short distance behind the forward edge of the blank, leaving a narrow marginal portion b of the blank projecting in advance of the carton. Shortly after the initial (assembly) contact of the blank and 100 carton the clamping fingers 10 are retracted to release the blank from the platen. In the further advance of the carton and blank, a portion of the blank is rolled into contact 105 with the bottom surface of the carton and the assembly consisting of the carton and wrapper blank then travels forward with a long trailing portion of the blank running over and supported by first the bands 13 and then the chains 15. Assuming the proper 110 placement of the blank on the platen as above described, the blank and carton will, therefore, be assembled in accurate registration because of the carefully coordinated 115 movements of the platen and conveyor chain 6, and this registration will be preserved by the conveyor bands 13 and chains 15 and 6, until the assembly arrives at the first wrapping position, so that the properly registered 120 wrapper is correctly wrapped and secured about the carton.

125 The wrapping machine as so far described, and in other respects as shown in the drawings, embodies certain modifications and improvements upon previous machines of its general type, as exemplified in the above-mentioned Patent No. 1,426,429; and such improvements, except as claimed herein in

connection with the sheet-feed mechanism, are described and claimed in a separate application.

The present invention more especially relates to means for properly supplying the individual wrapper blanks to the glue roll and then to the platen so that the blanks are properly located or registered on the platen and then by it are properly presented for registration on the packages or cartons in the manner above described.

The wrapper blanks used in wrapping machines of this sort, and handled by the present feed mechanism, may vary considerably, as to their size and outline. One typical form of blank, as sufficiently indicated in Fig. 4, has main or body sections *c*, *d*, *e*, *f*, side wings *g*, extending from the body portion *e*, flaps *h* extending from body portion *c*, flaps *i* extending from body portion *d*, flaps *j* extending from body portion *f*, and the marginal portions *b*, previously mentioned, extend from the long side of body portion *c*. The body portions *c* and *e* cover the top and bottom of the carton, the body portions *d* and *f* cover the (front and rear) vertical walls of the carton, the marginal flap *b* is turned up on the foremost side wall (in the direction of package advance) under the outer marginal portion of the flap *f*, which is subsequently affixed in the wrapping operations, the flaps *h*, *i* and *j* are folded up in a suitable order over the ends of the carton, marginal portions of these flaps overlapping, and the wings *g* being finally folded over to complete the end covering and sealing of the package. However the blanks may be shaped, they usually have outward straight edges at all four sides so that a stack of the blanks can be properly maintained in vertical alignment by suitable guide boards, as presently described.

A stack *S* of the blanks *B*, usually consisting of a large number of blanks to avoid frequent replenishment, is carried by a base-board or plate *40*, and this plate is removably located on the upper end of a vertical plunger *41* arranged to reciprocate in a sleeve *42* carried by a frame cross-piece *43*. The plunger is provided with a key or spline *44* to prevent it from rotating and it is provided with a toothed rack *45* engaged by a pinion *46* carried by a shaft *47* mounted in bearings *48*, so that by proper mechanism later described, the plunger may be raised to keep the top of the stack in proper position for the action of the sheet feed mechanism. The stack is guided by a front plate *50*, a back plate *51* and side plates *52* and *53*, supported by suitable framing.

Above the stack and near one side is located a stationary frame-member or open bracket *54*. A slide *55* is arranged to reciprocate horizontally on the inward vertical face of the bracket *54*, and is secured by

gibs *56*. The slide has a bearing sleeve *57* in which is mounted a shaft *58*, on one end of which is a hub *59* carrying an arm *60* having a yoke-shaped end *61*. A roll *62*, which may be identified as a "separator" or "pusher" roll, that is, the main or primary sheet separating instrumentality, is mounted on a shaft *63*, and the shaft is rotatably supported in the yoke *61* by adjustable conical bearings *64*. The roll proper *62*, is provided with one or more spaced cylinders *65* of suitable material, such as sponge rubber, to give proper contact and separating engagement with the wrapper blanks.

Slide *55* is reciprocated by a link *70* connected to a bell crank *71*, fulcrumed at *72*, and the bell crank is connected by a link *73* to a cam yoke *74* straddling shaft *21* and provided with a cam roller *75* running on the periphery of cam *76* secured to the shaft. The pusher roll *62* is raised and lowered to proper relation to the slide movement by the following mechanism: Shaft *58*, above mentioned, extends through the bearing sleeve *57* to a point in the opening of frame member *54*, where it is provided with a hub *80* having a lug *81*. A stop in the form of a screw *82* is adjustably secured in one end of the bracket *54* and secured in adjusted position by a lock-nut *83*. The inward end of this screw encounters lug *81* near the end of the advancing movement of slide *55* and raises the separator roll from contact with the upper sheet of the stack. Hub *59*, previously mentioned, is provided with a lug *85*, having a beveled face *86*. Adjacent to bearing sleeve *57* the slide *55* is provided with another bearing sleeve *87*, in which is mounted a rock shaft *88* carrying on one end adjacent to hub *59*, a latch arm *89* having a tooth or latch *90* to cooperate with lug *85*. When the pusher roll is elevated at the end of the advance stroke of the slide as above described, beveled face *86* of lug *85* raises the latch arm *89* and the latch *90* drops into engagement with the lug and retains arm *60* and the roller in elevated position out of contact with the stack while the slide retreats. The other end of rock shaft *88* carries a latch release arm *91* having a toe *92* arranged to engage, in the normal operation of the mechanism, near the end of the slide retreat, a stop *93*. This may, in some cases, be a fixed stop, and in such cases the rock shaft *88* is operated by the stop near the end of each return movement of the slide to raise latch *90* and permit the pusher roll to drop upon the stack.

It is desirable, however, in other cases to control the sheet feed action so that, for example, in a wrapping machine of the class described, if an article or package *C* is omitted from the package feed conveyor *6* or is absent at some other point in the movement of the articles or packages anterior to

the package conveyor, the feeding of a wrapper sheet which would correspond to the absent package or article, is omitted, and the wrapper blanks will only be fed and glued and presented at the assembly station when there is a package presented at that station for application to the wrapper. To provide for such feed control in the present instance the stop 93 is carried by a short

- 10 arm 94 fixed on one end of a rock shaft 95. This rock shaft is mounted in a bearing sleeve 96, and on the other end of the shaft is secured a curved arm 97, to the upper end of which is connected a link 98 leading to 15 a suitable feeler or detector mechanism adjacent to the line of package or article travel at a suitable point, so that whenever an article passes that point, which has a certain relation to the assembly position 20 corresponding substantially to the distance of travel of a wrapper sheet from the stack to assembly position, the feeler or detector mechanism acts through link 98 to maintain the stop 93 in active position so that 25 it releases the latch 90 in the manner above described, and causes the separator roll to feed a sheet, which reaches the assembly station at the proper time to be supplied to the package in question. In the absence 30 of a package, however, the feeler or detector mechanism does not move the link 98; rock shaft 95 is not oscillated, and stop 93 remains in inactive position away from the path of toe 92, and the latch 90 is, therefore, 35 not retracted, and the pusher roll remains in elevated position during the next advance movement of the slide 55, and no sheet is fed from the stack. The feeler or detector mechanism is not shown herein, but is described and claimed in combination with 40 other features of the wrapping machine in a separate application, Serial No. 588,354, filed September 15, 1922.

To permit the feeding of the top sheet 45 from the stack and restrain the next lower sheet during the withdrawal of the top sheet, pin detent mechanism is provided in general similar to such mechanism used in other sheet feed apparatus, but with certain improvements and features of adaptation to 50 the present feed mechanism as follows: On the back plate 51 or any suitable point of the framing, a lever 100 is pivotally mounted in a lug 101. The upper end of 55 this lever has a sleeve 102 in which a rod 103 is adjustably secured by a set screw 104. A hole is bored through the inward end of the rod, and in this hole a pointed 60 detent pin 105 is adjustably mounted and secured by a set screw 106 inserted in the end of the rod. The rod and pin may be adjusted in an obvious way and the point of the pin is arranged to pierce the upper wrapper blank near its rearward edge, particularly in the present case at a point near

the rear edge of the wrapper portion *f*, and the point of the pin, of course, indents or pierces more or less the next sheet or two or more of the sheets below the upper one, as circumstances may require. To further regulate the action of the pin detent a spring 107 is compressed between a portion of the back plate and the lower arm of the lever, and a screw 108 passes through a hole in the end of the lever arm and through the 75 spring, and enters a threaded hole in the back plate, and the screw-head 109 acts as a stop to limit outward movement of the lower lever arm. By adjusting the screw the amount of depression of the pointed end 80 of the pin 105 may be regulated and the number of sheets that it normally penetrates correspondingly regulated, with due regard for other features of the mechanism, such for instance, as the action of the stack 85 elevating mechanism.

As a sheet is advanced by the pusher roll its forward edge is brought into relation to primary feed rolls, stop and clamping mechanism. The upper member of the primary feed rolls actually consists in a preferred arrangement of at least two spaced feed rolls 120 fixed on a shaft 121, which is mounted in fixed bearings 122. Below the rolls 120 are similarly spaced movable 95 feed rolls 123 (sometimes called "ductor" rolls) fixed on a shaft 124 which is mounted in bearings 125. These bearings are carried by bearing blocks 126 having a short vertical movement in channels formed in upper 100 side members 127 of a vertically reciprocating slide or carrier 128, guided by ways or gibs 129 on the forward space of the front stack guide plate 50. The lower ends of the bearing blocks 126 are engaged by the upper 105 ends of screws 130 passing through lugs 131 in the slide side members 127, and the screws are secured in adjusted position by lock nuts 132. By adjustment of the screws the position of the shaft bearings 125 may be accurately adjusted, and in this way the proper engagement of the movable feed rolls 123 with the sheet, to clamp it against the upper feed rolls 120, when the carrier 128 is in upward position, is obtained.

Secured to the upper end of the carrier side members 127 is a blank clamping and stop plate 135, which has an upwardly curved rear face 136 to prevent upward deflection of an advancing blank and aid in 120 guiding the blank to the feed rolls. The plate has openings 137 to accommodate lower sectors of the upper feed rolls 120. The plate also has depending sheet stops 138 which have vertical rear faces to engage 125 the advancing edge of the sheet. To cooperate with the movable plate 135 is a lower adjustable, but normally fixed plate 140 having a rounded rearward face 141 to direct the sheet, and having forwardly extending 130

5 fingers 142 with flat upper faces 143 to cooperate with flat under surfaces 144 of plate 135 to clamp the sheet or blank. The plate 140 is secured to the forward stack guide plate 50 by screws 145 passing through slots 146 so that the plate may be adjusted vertically to insure the proper sheet clamping action.

6 The slide or carrier 128 is reciprocated by 0 a gear sector 150 engaging a rack 151 secured to a transverse member 152 of the slide. The gear sector 150 is pivotally mounted on a rock shaft 153 adjacent to a hub 154 secured to the shaft. This hub has 15 a lug 155 located in an opening 156 in an extension of the gear sector and screws 157 passing through upper and lower portions of the extension engage the lug so that the angular position of the gear sector may be 20 adjusted in relation to the shaft to properly position the carrier. Shaft 153 is oscillated by an arm 160 having a cam roller 161 engaging a cam groove 162 in a cam body 163 secured on shaft 164. Shaft 164 has a bevel 25 gear 165 engaged by a bevel gear 166 on a vertical shaft 167, and this shaft is driven by a bevel gear 168 engaging a similar gear on shaft 29, previously mentioned, this shaft being driven by idler gear 28 in the train of 30 gears running up from main shaft 21, as previously described. The cam groove 162 is contoured so that about the moment that slide 55 commences its feed movement (toward the left in Fig. 3), the plate 135 is 35 slightly elevated, and the clamping faces 143 and 144 are separated slightly more than the sheet thickness, but stops 138 are below the rear ends of plate fingers 142.

40 The slide 55 then moves to the left with roll 62 in engagement with the top sheet in the stack and by the rolling action of the pusher roll, or a combined rolling and pushing action depending on the adjustment of the roll bearings, the upper sheet is rolled 45 or pushed forward (to the left in Fig. 3). Its forward edge slides under plate 135 and over plate 140 and between the upper and lower primary feed rolls 120 and 123, which are now considerably separated, this separation 50 being shown in a somewhat exaggerated manner in Fig. 3, for the sake of clearness, until the forward edge of the sheet strikes the vertical faces of stops 138. There are 55 usually a plurality of these stops distributed laterally as sufficiently indicated in Fig. 5, so that the engagement of the sheet with the stops serves to straighten the forward edge of the sheet in the true transverse line parallel to the feed roll axes. The pusher 60 roll moves forward somewhat after the forward edge of the sheet is located against the stops, and in this further movement the sheet is more or less buckled upwardly between the pusher roll and a lower portion of the curved face of plate 135, as clearly

shown in Fig. 3. This further movement of the pusher roll and buckling of the sheet insures that the forward edge of the sheet will be accurately located and straightened against the stops. At about the moment that 70 slide 55 completes its feeding movement carrier 128 is lowered somewhat by a step or jog 170 in the cam groove 162 and the forward edge of the sheet is then securely clamped between the plates 135 and 140, 75 while the buckle in the sheet is still maintained and the location of the sheet insured until the clamping action is accomplished. At about this time the pusher roll is raised by the final advance movement of the slides 80 55, as previously explained, and the slide retreats. Shortly after the separator roll is raised, and after the sheet has had time to "settle" or flatten out by subsidence of the buckle, the carrier 128 is raised by the action 85 of cam groove 162 and the lower feed rolls 123 are thus elevated to clamp the sheet against the upper feed rolls 120.

90 While the mechanism so far described is sufficient in many cases for properly positioning or registering the sheet as it is delivered from the stack and before it is advanced by the gripper rolls, it is found that in some cases the pusher roll 62 pushes the paper against the stops 138 with sufficient 95 force to cause the front edge of the paper to be burred or wrinkled, and also that when the clamp releases the paper and the lower feed roll 124 is raised to grip and advance 100 the sheet, the paper does not readily release itself from the stops 138, but tends in some cases to follow the stop upward and jamming of the paper results. To prevent this, simple means are desirably provided to release the paper from the stops and also to 105 prevent improper burring or wrinkling, such means in one suitable embodiment being best shown in Figs. 6 and 7. The plate 135 is provided with slots intersecting the stops 138 and thin leaf springs 147 are located in 110 these slots and secured by screws 149. The springs are normally curved so that as shown in Fig. 6, before the paper is advanced in the initial feeding action the springs lie below the level of the clamping 115 faces 143 of plate 140. As the sheet is advanced from the stack, as shown in Fig. 7, it encounters the yielding resistance of the springs 147, and the springs are pushed upward to retain a yielding grip on the forward portion of the sheet and retarding its movement somewhat after the fashion of a 120 brake and the paper is prevented from striking the registering stop with too much force, and in this way burring or wrinkling of the forward edge is to a great extent avoided. The paper is then clamped in the manner 125 previously described and after the buckle has settled the paper is released from the 130 clamping faces and engaged between the

feed rolls, and as plate 135 rises the springs 147 move downward and push the advance edge of the sheet below the stop faces of stops 138. In other words, these springs act as strippers to insure the freeing of the sheet from the stops before it is fed forward by the gripper rolls.

The upper feed rolls 120 are continuously driven by a pinion 175 secured on shaft 121 and engaging idler gear 28, previously mentioned. The lower feed rolls are continuously driven by a pinion 176 on shaft 124 engaging a gear 177 on shaft 121, the pitch line diameters of the pinion and gear being proportional to the diameters of the respective rolls, and the teeth of the pinion and gear may be made long enough so that they remain in rotative engagement while the rolls are separated.

In front of the primary feed rolls is a slightly inclined paper shelf 180 supported by an extension 181 of the rear wall of the glue pot 4. Near the forward edge of this shelf and adjacent to the glue roll 17 are secondary blank feed rolls consisting of upper rolls 182, the individual rolls being usually separated by channels 183, and lower rolls 184, spaced in accordance with the spacing of the upper rolls. The forward portion of the shelf is slotted to accommodate the upper segments of the lower feed rolls. The upper and lower rolls are connected by pinions 186 and 187 mounted on their respective shafts; and the lower pinion 187 is driven by an idler pinion 188 which engages a gear 189 on glue roll shaft 18. In this way the secondary feed rolls are constantly driven at a suitable speed. Between the upper feed rolls 182 and the glue roll are guide fingers 190 carried by a transverse bar 191, these fingers having upright portions 192 and lower portions 193 parallel to the plate 180 and spaced above it slightly more than the sheet thickness, the rearward ends of the guide portions 193 being located in the channels between the upper feed rolls.

The forward edge of the wrapper blank is gripped by the primary feed rolls after the pusher roll 62 is raised and after the sheet has settled flat upon the stack. The engagement of the sheet between two laterally separated sets of feed rolls driven at the same speed insures the sheet against lateral or angular displacement. The sheet is now fed forward by the primary feed rolls over the plate 180 and its forward edge is gripped between the secondary feed roll and advanced under the guide members 193 into contact with the glue surface of the glue roll 17; the foremost edge of the sheet is deflected upward and is carried round the glue roll to substantially the uppermost point thereof where it is stripped from the roll by the stripper plates 20; shortly thereafter the forward edge of the

blank is brought against the platen stops 9 in perfectly true alinement and is gripped by the fingers 10; the blank is then carried around by the platen and rearward portions of the blank surface are drawn over the glue roll, the secondary feed rolls continuing to positively feed the blank until its rear edge leaves them; the platen carries the glued blank around to a point adjacent to the rear end of table 5 and the blank is associated with an advancing carton or article in the manner previously described. Since the wrapper blank, by the described mechanism and operations is accurately fed in properly timed relation to the platen, and is kept in proper alinement and so delivered to the platen, the correct presentation of the blank in properly registered position at the assembly station is insured.

As successive blanks are removed from the stack S the top of the stack is lowered and it is necessary to elevate the stack gradually or intermittently at sufficiently frequent intervals to keep the upper sheet at approximately the same level, and to control the lifting mechanism in a proper way to produce this result. While in the broader aspect of the invention various means for controlling the lifting mechanism may be employed, it is desirable to provide controlling mechanism which is regulated by the actual position of the uppermost sheet of the stack so that the lifting mechanism will operate in accordance with the actual momentary position of the stack top. In this way any variation in the rate at which sheets are removed from the stack is automatically taken care of. For instance, if one or a number of successive packages are absent from the package conveyor and the sheet feed mechanism is rendered inoperative during one or several successive cycles in the manner previously explained, the lifting mechanism is controlled so that the stack is not lifted until the feed of sheets is resumed and a sufficient number of sheets is removed to call for a repositioning of the stack.

The shaft 47 with its pinion 46 engaging the rack on the stack supporting plunger 41, is provided with a gear 200 which is engaged by a pinion 201 on a shaft 202. This pinion is operatively fixed in relation to a circular ratchet 203. The ratchet is engaged by a holding pawl or detent 204 and by a driving pawl 205 carried by a lever 206 fulcrumed on the axis of shaft 202 and the pawl 205 is urged to engage the ratchet by any suitable spring arrangement. The other end of lever 206 is pivotally connected to a vertical rod 210 arranged to reciprocate in stationary guide sleeves 211. The upper end of this rod is connected by a link 212 to an arm 213 carried by a rock shaft 214 and on the inward end of the rock shaft

is another arm 215 connected by a link 216 to an arm 217 on a rock shaft 218 mounted in bearings on the upper end of the rear stack guide plate 51. Rock shaft 218 has a forward projecting arm 220 terminating in a plate or presser finger 221 arranged to bear on the top of the stack. Slidably mounted on vertical rod 210 is a block 225 having a collar engaged by the forked end 5 of a bell crank lever 228 fulcrumed at 229 and provided with a cam roller 230 engaging a cam groove in cam body 163 previously mentioned, the last named cam groove being on the opposite side of the body from 10 cam groove 162 which actuates carrier 128. The sliding block has an extension 240 provided with a vertical spring rod 241 passing through a lug 242 secured to rod 210, and a helical spring 243 is located about the 15 spring rod between extension 240 and lug 242. The upward travel of the block 225 on rod 210 is limited by an adjustable stop nut 245 and lock nut 246 having threaded engagement on rod 210.

20 In every cycle of the mechanism the bell crank 228 is oscillated by its cam groove. After the pusher roll 62 has fed a sheet forward sufficiently for its rear edge to clear the plate or presser finger 221, block 225 is moved down by the bell crank 228. The 25 spring 241 impels rod 210 downward along with the block until the presser finger 221 engages the top of the stack and compresses the stack somewhat, more or less, depending 30 on the stiffness of the spring. The spring is then compressed and the block 225 slides down on rod 210 and away from the stop nut 245 a short distance as shown in Fig. 5. During the downward movement of rod 35 210 until this movement is checked by engagement of the finger 221 with the stack, the right hand end of lever 206 as viewed in Fig. 1, is raised and the pawl 205 slides up over the outer face of one of the teeth 40 of the circular ratchet 203. If the position of the top of the stack is such that the presser finger 221 cannot descend far enough to permit the pawl 205 to pass over the point of one of the ratchet teeth, upon 45 the return movement of lever 206 caused by the reverse movement of bell crank 228, the pawl will simply slide back over the outer face of the ratchet tooth without turning the ratchet or elevating the stack. When 50 the bell crank moves in the reverse direction as just above described, clearance between the block 225 and stop nut 245 is first taken up and then the rod 210 is lifted raising the presser finger 221 from the stack and at 55 the same time retracting the pawl 205. After a number of sheets have been withdrawn from the top of the stack, the number depending on the thickness of the sheets and the adjustment of the mechanism, in one of 60 the descending movements of the presser 65 finger 221 the pawl 205 is allowed to retract far enough to "pick up" one tooth of the ratchet and on its forward movement drives the ratchet forward one tooth space, and this motion is communicated through 70 the gear connections to the stack plunger 41, and the stack is lifted to restore the position of the upper sheet in proper relation to the feed mechanism. Since the drive from the circular ratchet to the stack plunger may 75 be a reduction drive, as shown by the relative sizes of the gear members in the present instance, the ratchet teeth may be made relatively coarse and the movement of the pawl lever 206 may be of substantial ampli- 80 tude without lifting the stack too much at any one lifting action. The lift at any one action may moreover be varied by adjustment of the stop nut 245, or in other ways, as will be sufficiently understood without 85 further description.

While, as above stated, general features of the wrapping machine, as here shown, and details of the platen, glue roll, etc., are not claimed here apart from their relation 90 to the paper or blank feed mechanism, it will be understood that in the broader aspect of the invention, the platen and the glue roll, as well as the feed rolls, form parts of the train of mechanism actually engaged in feed- 95 ing or advancing the sheets or blanks to the registration point, and, therefore, these parts of the mechanism are claimed herein in connection with, or in combined relation to, or as subordinate parts of the sheet or blank 100 feed mechanism.

An important feature of the blank feed mechanism proper is that it dispenses with complications and other objectional features incident to suction feed apparatus, which is 105 frequently employed in sheet feed mechanism, and at the same time provides individual sheet feeding means, which is more positive and accurate in its operation for the 110 present purpose.

In one aspect of the invention, the pusher roll 62 is representative of any suitable means for advancing individual sheets or successive sheets to registering mechanism including the stops 138 by which the sheets 115 are alined and registered with reference to a subsequently acting device such as the rotary platen or platen grippers, and are then advanced by suitable means such as the feed rolls 120 and 123 with preservation of their registered positions past means for adhesively conditioning the sheets, such means being represented in the present embodiment by the glue roll 35, so that the advance edge of each sheet arrives at a proper point for manipulation by the rotary platen at the proper time, and is, in fact, in the present embodiment, definitely registered on the platen by movement of the 120 advance edge of the sheet against the platen 125

65 70 75 80 85 90 95 100 105 110 115 120 125 130

stops 9, whereupon the sheet is seized by the platen grippers 10 and then advanced in properly registered position to a delivery point, which in the present example is a point near the upper surface of the platen where the glued sheet is associated with an article such as a filled carton.

What we claim is:—

1. Sheet-feed mechanism comprising a stack holder, a pusher roll adapted to move individual top sheets from the stack laterally by roll engagement, a roll carrier, and adjustable conical roll bearings to regulate the sheet pushing action of the roll.
- 15 2. Sheet-feed mechanism comprising a holder for a sheet stack, a sheet stop close to the stack and arranged to be engaged by the advancing edge of a sheet, means for moving individual sheets from the stack against the stop, and means for advancing the sheets and maintaining their front registered position after they are positioned against the stop.
- 25 3. Sheet-feed mechanism comprising a holder for a sheet stack, a row of sheet stops close to the stack and arranged to engage and align the advancing edge of a sheet, means for moving individual sheets from the stack against the stops, and means for advancing the sheets and maintaining their front registered position after they are positioned against the stops.
- 30 4. Sheet-feed mechanism comprising a sheet stack holder, a sheet stop near the top of the stack, means for feeding individual sheets against the stop and for buckling the sheets to insure proper location, means for withdrawing the stop, means for clamping sheets located by the stop, and means for gripping and removing sheets after release from the clamping means.
- 40 5. Sheet-feed mechanism comprising a sheet stack holder, a sheet stop near the top of the holder stack, means for feeding individual sheets edgewise against the stop, sheet clamping means, and means for gripping and feeding sheets away from the stack after positioning and clamping.
- 50 6. Sheet-feed mechanism comprising a sheet stack holder, a feed roll near the top and at one side of the stack, a cooperating feed roll, a retractable sheet stop, sheet clamping means, means for pushing individual sheets between the feed rolls and against the stop, and operating mechanism for withdrawing the stop, moving the clamping means to clamp and remove the sheet, and causing the feed rolls to grip and advance the sheet.
- 55 7. Sheet-feed mechanism comprising a sheet stack holder, a fixed feed roll near the top and at one side of the stack, a cooperating movable feed roll, a retractable sheet stop, sheet clamping means, means for pushing individual sheets between the feed rolls

and against the stop, and operating mechanism for withdrawing the stop, moving the clamping means to clamp and remove the sheet, and moving the movable feed roll to grip and remove the sheets from the stack.

70

8. Sheet-feed mechanism comprising a sheet stack holder, a fixed feed roll at the top and near one side of the stack, a fixed sheet clamping member adjacent to said roll, a movable carrier, a movable feed roll mounted on the carrier to cooperate with the fixed roll, and a sheet clamping member on the carrier arranged to cooperate with said fixed sheet clamping member.

75

9. Sheet-feed mechanism comprising a sheet stack holder, a feed roll on a fixed axis at the top and near one side of the stack, a fixed sheet clamping member adjacent to said roll, a movable carrier, a movable feed roll mounted on the carrier to cooperate with the fixed roll, a sheet stop on the carrier, and a sheet clamping member on the carrier arranged to cooperate with said fixed sheet clamping member.

80

10. Sheet-feed mechanism comprising a sheet stack holder, a feed roll on a fixed axis at the top and near one side of the stack, a fixed sheet clamping member adjacent to said roll, a movable carrier, a movable feed roll mounted on the carrier to cooperate with the fixed roll, a sheet stop on the carrier, a sheet clamping member on the carrier arranged to cooperate with said fixed sheet clamping member, and means for pushing individual sheets edgewise from the top of the stack between the feed rolls and against the stop.

85

11. Sheet-feed mechanism comprising a sheet stack holder, a feed roll on a fixed axis at the top and near one side of the stack, a fixed sheet clamping member adjacent to said roll, a movable carrier, a movable feed roll mounted on the carrier to cooperate with the fixed roll, a sheet stop on the carrier, a sheet clamping member on the carrier arranged to cooperate with said fixed sheet clamping member, means for pushing individual sheets edgewise from the top of the stack between the feed rolls and for buckling the sheets against the stop, and means for moving said carriage to and fro in timed relation to the sheet pushing means.

90

12. Sheet-feeding mechanism comprising a holder for a vertical stack of sheets, means for moving individual sheets laterally from the stack top, and sheet detent mechanism comprising a pivoted lever, an arm on the lever, a detent pin in the arm and arranged to pierce the upper sheet near one edge, a spring acting on the lever to engage the pin with the stack, and a stop to limit the engaging movement of the pin.

95

13. Sheet-feeding mechanism comprising a holder for a vertical stack of sheets, means for pushing individual sheets laterally from

100

the stack top, and sheet detent mechanism comprising a pivoted lever, an arm adjustable on the lever, a detent pin adjustable in the arm and arranged to pierce the upper sheet near one edge, a spring acting on the lever to engage the pin with the stack, and an adjustable stop to limit the engaging movement of the pin.

5 14. Sheet-feed mechanism comprising a holder for a sheet stack, a sheet stop adjacent to the stack and arranged to be engaged by the advancing edge of a sheet, means for moving individual sheets from the stack against the stop, means for retarding movement of the sheet adjacent to the stop, and means for advancing the sheets and maintaining their registration after they are positioned against the stop.

10 15. Sheet-feed mechanism comprising a holder for a sheet stack, a sheet stop adjacent to the stack and arranged to be engaged by the advancing edge of a sheet, means for moving individual sheets from the stack against the stop, a yielding member engaging the advancing portion of the sheet and retarding its movement adjacent to the stop, and means for advancing the sheets and maintaining their registration after they are positioned against the stop.

15 16. Sheet-feed mechanism comprising a holder for a sheet stack, a sheet stop adjacent to the stack and arranged to be engaged by the advancing edge of a sheet, means for moving individual sheets from the stack against the stop, means for retracting the stop, means for releasing the advance edge of the sheet from the stop, and means for advancing the sheets after they are positioned against the stop.

20 17. Sheet-feeding mechanism comprising a sheet-stack holder, a retractable sheet stop positioned nearly in line with the upper stack sheet, means for advancing individual top sheets successively against the stop, with excess movement to insure proper sheet location, means for retracting the stop after a sheet is positioned, means for retarding the sheet adjacent to the stop, and means for gripping and removing the sheet from the stack.

25 18. Sheet-feeding mechanism comprising a sheet-stack holder, a retractable sheet stop positioned nearly in line with the upper stack sheet, means for advancing individual top sheets successively against the stop, with excess movement to insure proper sheet location, means for retracting the stop after a sheet is positioned, a yielding sheet engaging member to retard sheet movement adjacent to the stop and to strip the sheet from the stop when the latter is retracted, and means for gripping and removing the sheet from the stack.

30 19. Sheet-feeding mechanism comprising a sheet-stack holder, a retractable sheet stop

positioned nearly in line with the upper stack sheet, means for advancing individual top sheets successively against the stop, with excess movement to insure proper sheet location, means for retracting the stop after a sheet is positioned, means for stripping the advance edge of the sheet from the stop as the stop is retracted, and means for gripping and removing the sheet from the stack.

35 20. In sheet-feed mechanism, means for guiding a vertical sheet stack, a retractable stop adjacent to the top of the stack, means for advancing individual sheets against the stop with excess movement to provide a buckle, means for retarding the sheet adjacent to the stop and for stripping the feed from the stop when the stop is retracted, means for clamping the sheet after positioning against the stop, means for retracting the stop, and means for gripping and advancing the registered sheet after the stop is retracted.

40 21. Sheet feed mechanism comprising feed rolls, a stop adjacent to the contact line of the feed rolls, means for moving the stop to active position and concurrently moving one of the feed rolls to inactive position, means for moving a sheet edge-wise and buckling it against the stop and means for thereafter retracting the stop and moving said last named feed roll to grip the sheet against the other roll and advance it in registered position.

45 22. Sheet feed mechanism comprising a shelf, a feed roll on a fixed axis and spaced slightly above the shelf, a cooperating movable feed roll, sheet aligning stops movable to active position adjacent the shelf and in front of the edge of an advancing sheet, means for pushing a sheet edge-wise between the shelf and the fixed roll and buckling it against the stops, and means for thereafter retracting the stops and moving the movable feed roll to grip and advance the sheet in registered position.

50 23. Sheet feed mechanism comprising a stack holder, a shelf adjacent to the stack top, a feed roll on a fixed axis and spaced slightly above the shelf, a co-operating feed roll arranged for movement toward and from the fixed roll, sheet aligning stops movable to active position above the rear edge of the shelf and in front of the edge of an advancing sheet, means for pushing the top sheet from the stack edge-wise between the shelf and the fixed roll and against the stops with excess motion to insure proper feed alignment, and means for thereafter retracting the stops and moving the movable feed roll to grip and advance the sheet in registered position.

55 24. Sheet feed mechanism comprising a stack holder, feed rolls close to the stack top, retractable sheet aligning stops adjacent to the feed roll contact line, a shelf

over which a sheet is positioned close to one of the feed rolls, means for moving a single sheet edgewise from the stack over the shelf and against the stops when the latter are in active position, and yieldable sheet clamping means cooperating with the shelf to retard and yieldably hold the sheet as aligned and registered by the stops.

25. Sheet feed mechanism comprising a stack holder, feed rolls close to the stack top, retractable sheet aligning stops adjacent to the feed roll contact line, a shelf over which a sheet is positioned close to one of the feed rolls, means for moving a single sheet edgewise from the stack over the shelf and against the stops when the latter are in active position, and yieldable sheet clamping means cooperating with the shelf to retard and yieldably hold the sheet as aligned and registered by the stops, and means acting after the sheet is aligned and yieldably held to retract the stops and con-

currently grip the sheet between the feed rolls and advance it with maintained registration.

26. Sheet feed mechanism comprising a holder for a stack of sheets, feed rolls close to the stack top, retractable sheet aligning stops adjacent to the feed roll contact lines, a shelf over which a sheet is positioned close to one of the feed rolls, means for moving a single sheet edgewise from the stack over the shelf and against the stops when the latter are in active position, and yieldable sheet clamping means cooperating with the shelf to retard and yieldably hold the sheet as aligned and registered by the stops, said means acting when the stops are retracted to free the sheet edge therefrom.

Signed at Philadelphia in the county of Philadelphia and State of Pennsylvania this 29th day of May A. D. 1922.

WILLIAM A. WEIGHTMAN.
